UNITED STATES PATENT OFFICE.

MAURICE F. JONES, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

1,384,469.

Specification of Letters Patent. Patented July 12, 1921.

Application filed August 3, 1917. Serial No. 184,238.

To all whom it may concern:

Be it known that I, MAURICE F. JONES, a citizen of the United States, and a resident of Wilkinsburg, in the county of Allegheny and State of Pennsylvania, have invented a new and useful Improvement in Control Apparatus, of which the following is a specification.

My invention relates to control apparatus and especially to arc-extinguishing means in connection with coöperating contact members of the familiar unit-switch type.

The object of my invention is to provide a device of the above-indicated character, wherein a fluid blast is directed upon coöperating electrical contact members substantially only during the period of existence of an arc between them.

More specifically stated, the object of my invention is to provide a fluid-pressure type of arc-extinguishing means that is dependent for its operation upon the opening movement of the contact members and wherein the extinguishing fluid blast is automatically cut off upon the rupture of the arc, such automatic operation being obtained through the medium of an actuating coil for the fluid-directing means that is connected in series relation with the contact members.

My invention may best be understood by reference to the accompanying drawing, wherein Figure 1 is a view, partially in elevation and partially in section, of a complete unit-switch apparatus embodying my invention; Fig. 2 is a diagrammatic view of a control system serving to illustrate the preferred circuit connections of the apparatus that is shown in Fig. 1; and Fig. 3 is a semi-diagrammatic view, corresponding to Fig. 1, of a modification of the invention.

Referring to Fig. 1 of the drawing, the illustrated structure comprises a suitable insulating base-plate or cover member 1 for the purpose of supporting a series of stationary contact members 2 and of coöperating movable contact members 3 of the familiar unit-switch type, for controlling any desired circuit connections; a remotely-controlled power-operated means 4 for actuating the movable contact member 3 to its closed posi-

tion; a fluid-pressure valve 5 for governing the fluid blast for extinguishing arcs that are caused by the separation of the contact members; and electromagnetic means 6 for controlling the operation of the fluid valve 5 in conjunction with the movement of the contact members, as hereinafter described in detail.

The stationary contact member 2 comprises a conducting terminal member or mounting-block 10 which may be secured to the supporting plate 1 through the agency of suitable screws 11, for example, and a copper terminal tip 12 which is electrically associated with the block 10 in any appropriate manner. The terminal block 10 has an internal passage 13 which acts in the capacity of a nozzle for directing a fluid blast upon and between the coöperating stationary and movable contact members during their separation, as hereinafter more fully set forth. A fluid delivery pipe 14 effects communication with the passage 13, preferably through an insulating tubular knob or disk 15, one end of the pipe 14 leading into the fluid valve 5. It will be understood that, if desired, a suitably designed nozzle or pipe may be secured to the terminal block 10 and employed in lieu of the internal passage 13 for the above-mentioned purpose.

The movable contact member 3 comprises a contact tip 16 which is similar to the tip 12 and which is mounted upon an oscillating arm 17 that has a pivotal connection 18 with a main switch arm 19. The main arm 19, in turn, is pivotally mounted upon a bracket or standard 20, which is appropriately attached to the supporting plate 1. The general construction of the movable contact member 3 is of a well-known form and serves the purpose of providing a "wiping" action of the coöperating contact members during the contact-making and breaking thereof, in accordance with familiar principles. In particular, abutting inclined surfaces 21 and 22 upon the oscillating arm 17 and the main switch arm 19, respectively, are utilized during the action just recited, serving to define the limit of movement of the oscillating arm 17, which, in the figure, is illustrated as occu-

pying its normal fully open position. A coil spring 23 is utilized to bias the oscillating arm 17 to the position shown, wherein the inclined surfaces 21 and 22 make contact.

5 The actuating mechanism 4 is of a familiar electrically-controlled pneumatically-operated type, comprising a pneumatic engine having an incasing cylinder 25 within which travels a piston 26 that is normally biased to 10 the illustrated position by a coil spring 27. The piston 26 is provided with a suitable stem or rod 28, which is mechanically coupled, through the medium of an insulating disk or knob 29, to a hook member 30 that 15 engages the main switch arm 19. The upward piston movement is effected through the agency of a normally closed fluid valve 31 which, when opened through the electromagnetic action of a coil 32 that is governed in 20 the customary manner, serves to effect the conveyance of fluid pressure from any suitable source (not shown) through a supply pipe 33, the open internal passages of the valve 31 and a delivery pipe 34 to the operating cylinder 25.

The fluid valve 5 may be of any suitable form, comprising a plug valve 35 that is normally seated in its illustrated uppermost position to cut off communication between 30 a fluid-supply pipe 36 and the delivery pipe 14, which leads into the nozzle passage 13 of the stationary contact member 2. The stem of the plug valve 35 has a pivotal connection 37 with a lever arm 38 which, in 35 turn, is pivotally mounted upon a bracket or standard 40 that is suitably secured to the base-plate 1. A relatively powerful spring 41 is located between the free end of the lever arm 38 and the main switch arm 19 of 40 the movable contact member 3. The spring 41 is thus located directly beneath the plug valve 35 and, during the illustrated fully open condition of the contact members and also during the subsequently-described completely closed condition of the contact members, the compression of the spring 41 serves 45 to bias the plug valve member 35 to its upper or inoperative position.

The electromagnetic means 6 comprises 50 an incasing member 45 of magnetizable material; an actuating coil 46 of relatively heavy strap wire, for example, for carrying the full current that traverses the contact members 2 and 3; and a movable magnetizable core member 47 which is mounted upon a reciprocating rod 48, the upper end of which is pivotally associated with an intermediate portion of the lever arm 38. A coil spring 49, acting between the lever arm 38 55 and the incasing member 45 of the electromagnetic means 6, serves to normally aid in biasing the lever arm 38 and the fluid valve 5 to the illustrated closed positions, although the arrangement of parts is such that 60 the turning movement of the spring 49 is

less than that of the spring 41, under compression, for a purpose to be hereinafter set forth.

The actuating coil 46 for the electromagnetic means 6 is provided with terminal conductors 50 and 51 which are connected in circuit in a manner to be described in connection with Fig. 2. The conductor 51 is electrically secured to the main switch arm 19 of the movable contact member 3 by 70 means of screws 52, for example. In so far as Fig. 1 is concerned, the electrical circuit is continued from the terminal conductor 50 through the actuating coil 46, conductor 51, main switch arm 19, oscillating arm 17, 75 movable contact tip 16, stationary contact tip 12 and mounting-block 10 to terminal conductor 53.

Referring to Fig. 2, the simplified illustrated system comprises supply-circuit conductors trolley and ground; a dynamo-electric machine having a commutator-type armature A¹ and a field winding F¹ of the series type; and the various circuit elements of the structure illustrated in Fig. 1. The 80 machine circuit is established from the trolley through the conductor 50, the actuating coil 46 of the electromagnetic means 6, the conductor 51, the movable and stationary contact tips 16 and 12, respectively, the conductor 53, armature A¹, field winding F¹ and 85 a conductor 54 to the negative supply-circuit conductor ground.

In the illustrated system, the contact members 12 and 16 are thus utilized in the 100 capacity of a line switch, although it will be understood that my invention is not so restricted in its application and may be employed in connection with any set of coöperating contact members that are employed 105 to open an electric circuit.

Assuming that the various parts of the apparatus occupy the positions illustrated in Fig. 1, the complete operation thereof may be set forth as follows: Upon the energization of the actuating coil 32 of the power-operated mechanism 4, the valve 31 is actuated to its open position to admit fluid pressure to the operating cylinder 25 and thus raise the piston 26 to its upper position, such movement being transmitted through the hook member 30 and the coöperating elements of the movable contact member 3 to effect the closure thereof; that is, the intimate engagement thereof with the stationary contact tip 12, in accordance with the previously-mentioned "wiping" contact motion. The governed circuit is thus closed, and current traverses the various illustrated circuit elements.

Consequently, the magnetizable core member 47 of the electromagnetic means 6 is downwardly attracted by the electromagnetic action of the coil 46 but the spring 41, when under compression, as in the case of 130

the closed condition of the contact members 2 and 3, predominates over such electro-magnetic action and, therefore, the fluid valve 5 remains in its closed position.

5 Upon deenergization of the coil 32 of the actuating mechanism 4, the spring 27 immediately returns the piston 26 to its illustrated lower position and the movable contact tip 16 is somewhat more slowly separated from the stationary contact tip 12 by reason of the previously-mentioned "wiping" action. During the initial portion of the contact-opening movement, the biasing spring 23 serves to maintain the engagement of the co-operating contact members until the inclined surfaces 21 and 22 of the movable contact member 3 make contact. By this time, the main switch arm 19 has been lowered a distance sufficient to relieve the greater part of the initial compression in the spring 41 and, consequently, the relatively weak opposing action of the spring 49, with respect to the attraction of the actuating coil 46 upon the core member 47, permits the downward movement of the lever arm 38, thus opening the fluid valve 5. Air or other suitable fluid-pressure medium is thereupon conveyed from the supply pipe 36 through the pipe 14 to the internal passage 13, and the nozzle action, thus established at the outlet of the passage 13, serves to direct a powerful fluid blast upon and between the contact tips 12 and 16. The preferred arrangement of parts is such that the fluid blast is commenced just prior to the initial complete separation of the two contact tips, whereby the arc-extinguishing blast is effective before the arc itself has actually formed.

40 As the contact tips become further separated, the usual heavy arc is formed, but it is soon extinguished by reason of the action of the fluid blast just recited. Until the arc has been ruptured, the traversal of current through the actuating coil 46 of the electro-magnetic means 6 is maintained to hold open the fluid valve 5. Upon the arc rupture and the resultant deenergization of the actuating coil 46, the powerful spring 41 immediately returns the plug valve 35 to its upper seat, and the magnetizable core 47 is likewise elevated to the illustrated initial position.

45 My invention is thus adapted to provide a very effective and reliable arc-extinguishing means in connection with electrical contact members, the complete rupture of the arc being insured by reason of the fact that the fluid blast is maintained until such rupture has actually occurred, while, by proper design of parts, the fluid blast is utilized substantially only during the period of existence of such an arc, thus making for economy in operating costs.

50 In lieu of employing my invention by

itself for the purpose of extinguishing arcs between separating contact members, it will be understood that the device may be utilized in a protective or emergency capacity to supplement the action of the familiar magnetic blow-out devices that have been heretofore associated with controllers of the unit-switch type.

55 With such a combined device, in the case of a short-circuit or other severe operating condition in the control system, the fluid-pressure type of arc-extinguishing means for the opening contact members may be brought into action by the electromagnetic means 6 which, in this instance, needs to be 60 provided with only a relatively small number of coil turns. Thus, under normal current-interrupting conditions, only the customary magnetic-blowout action is established, while, under emergency conditions, 65 the electromagnetic means 6 is sufficiently energized to open the valve 5 and thus supplement the action of the magnetic blowout by directing a fluid blast upon the arc.

70 Reference may now be had to Fig. 3, 90 wherein is shown a system for electrically effecting the operation of an arc-extinguishing fluid blast in lieu of mechanically controlling the valve 5, as shown in Fig. 1.

75 The structure illustrated in Fig. 3 comprises the base-plate 1 and the stationary and movable contact members 2 and 3, respectively, together with the actuating mechanism 4 for the movable contact member and, in addition, a fluid-controlling 80 valve 60; a series relay device 61; an electrical interlock or set of auxiliary contact members 62 that are controlled by the action of the movable contact member 3; and an auxiliary source of energy, such as a battery B.

85 The fluid-controlling valve 60 comprises a delivery pipe or passage 64 that communicates with the nozzle passage 13; a movable valve member 65 which normally prevents 90 communication between the delivery pipe 64 and a supply pipe 66; a magnetizable core member 67 which is secured to the valve member 65; a spring 68 which may be secured to the core member 67 to bias the valve 95 to the illustrated closed position; and an actuating coil 69 for moving the valve member 65 to the open position when the coil is energized to direct a fluid blast through the nozzle passage 13 upon the main contact 100 members.

105 The relay device 61 comprises a magnetizable core member 75 to which is attached a bridging contact member or disk 76, which closes an auxiliary circuit, to be set forth, 110 when an actuating coil 77 is energized through the main contact members.

115 The interlocking contact members 62 are of a familiar type in unit-switch controllers, comprising a supporting arm 80, which is 120

rigidly secured to the piston stem 28 of the actuating mechanism 4 and upon which is mounted a suitably insulated contact block or segment 81 to engage a spring contact 5 finger or clip 82 in the opened condition of the main contact members.

Assuming that the main contact members have been closed in the manner described in connection with Fig. 1, the main circuit is 10 established from the conductor 50 through the actuating coil 77 of the relay device 61, which is thus closed, conductor 83 and thence, through the movable and stationary main contact members 3 and 2, respectively, 15 to the terminal conductor 53. Under such conditions, the electrical interlock 62 is opened and, consequently, the actuating coil 69 of the fluid controlling valve 60 remains deenergized.

20 Upon the opening movement of the main contact members, however, the relay device 61 remains in its closed or energized position by reason of the formation of an arc between the main contact tips 12 and 16 and, more 25 over, as soon as the movable contact member reaches a predetermined open position, the electrical interlock members 81 and 82 engage to complete an auxiliary circuit from the positive terminal of the battery B 30 through conductor 85, stationary contact finger 82 and movable contact segment 81 of the electrical interlock 62, conductor 86, movable contact member 76 of the contact segment 61 in the upper or closed position, 35 conductor 87, actuating coil 69 of the fluid-controlling valve 60 and conductor 88 to the negative terminal of the battery B.

The arrangement of parts is preferably made such that the opening impulse is im- 40 parted to the valve member 65 just prior to the actual separation of the main contact tips 12 and 16 which, as previously mentioned, produce a "wiping" action upon each other before such actual separation 45 takes place. Consequently, a fluid blast is maintained upon and between the main contact members until the arc has been ruptured to deenergize the actuating coil 77 of the relay device 61, whereupon the opening move- 50 ment of the relay device deenergizes the actuating coil 69 of the fluid-controlling valve 60 to permit the spring 68 to return the valve member 65 to its illustrated closed position.

55 I do not wish to be restricted to the specific structural details or arrangement of parts herein set forth; as various other modifications of my invention may be effected without departing from the spirit and scope 60 thereof. I desire, therefore, that only such limitations shall be imposed as are indicated in the appended claims.

I claim as my invention:

1. In control apparatus, the combination 65 with a plurality of normally open electrical

contact members, of means for actuating one of said contact members to a closed position, a valve opened by the opening movement of the contact members to direct a fluid blast upon the arc caused by their separation, and 70 a coil in series circuit with said arc and associated with means for automatically permitting the closure of said valve only upon the rupture of the arc.

2. In control apparatus, the combination 75 with a plurality of normally open electrical contact members, of means for actuating one of said contact members to a closed position, a fluid-pressure supply passage for directing a fluid blast upon the arc caused by the separation of said contact members, a valve for regulating the fluid supply to said passage, means for biasing said valve to the closed position under normal closed and normal open conditions of the actuatable contact member, a magnetizable member mechanically associated with said valve, and an actuating coil for said magnetizable member connected in series circuit with said arc to effect the 80 opening of said valve.

3. In control apparatus, the combination 85 with a plurality of normally open electrical contact members, of means for actuating one of said contact members to a closed position, a fluid-pressure supply passage for directing a fluid blast upon the arc caused by the separation of said contact members, a normally closed valve for regulating the fluid supply to said passage, and means electrically dependent upon the formation of such an arc 90 and also upon the opening movement of the contact members for opening said valve.

4. In control apparatus, the combination 95 with a plurality of normally open electrical contact members, of means for actuating one 100 of said contact members to a closed position, a fluid-pressure supply passage for directing a fluid blast upon the arc caused by the separation of said contact members, a normally closed valve for regulating the fluid supply to said passage, and electro-magnetic 105 means energized upon the formation of such an arc when the actuatable contact member occupies a predetermined open position to open said valve.

5. In control apparatus, the combination 110 with a plurality of normally open electrical contact members, of means for actuating one of said contact members to a closed position, a fluid-pressure supply passage for directing a fluid blast upon the arc caused by the separation of said contact members, a normally closed valve for regulating the fluid supply to said passage, a relay device having an actuating coil energized through said contact 115 members, and means for opening said valve when said relay-device coil is energized and said actuatable contact member occupies a predetermined open position.

6. In control apparatus, the combination 120

with a plurality of normally open main electrical contact members, of means for actuating one of said contact members to a closed position, a fluid-pressure supply passage for directing a fluid blast upon the arc caused by the separation of said contact members, a normally closed valve for regulating the fluid supply to said passage, a relay device having an actuating coil energized through said main contact members and having auxiliary contact members, a set of auxiliary stationary and movable contact mem- bers associated with said actuatable main contact member, and an actuating coil for opening said valve, said coil being energized through all said auxiliary contact members only when said relay device is energized and said actuatable main contact member occupies a predetermined open position. 15

In testimony whereof, I have hereunto 20
subscribed my name this 26th day of July
1917.

MAURICE F. JONES.
